(57) **CLAIM**

We claim the ornamental design for a combined steering block and C-hub for a model vehicle, as shown and described.

DESCRIPTION

FIG. 1 is a right elevation view of a steering block of the combined steering block and C-hub for a model vehicle, shown separately for the ease and clarity of illustration;

FIG. 2 is a left elevation view thereof;

FIG. 3 is a rear elevation view thereof;

FIG. 4 is a front side elevation view thereof;

FIG. 5 is a top plan view thereof;

FIG. 6 is a bottom plan view thereof;

FIG. 7 is a top, front, left perspective view thereof;

FIG. 8 is a right elevation view of a C-hub of the combined steering block and C-hub for a model vehicle, shown separately for the ease and clarity of illustration;

FIG. 9 is a left elevation view thereof;

FIG. 10 is a rear elevation view thereof;

FIG. 11 is a front side elevation view thereof;

FIG. 12 is a top plan view thereof;

FIG. 13 is a bottom plan view thereof;

FIG. 14 is a top, front, left perspective view thereof;

FIG. 15 is a right elevation view of a combined steering block C-hub;

FIG. 16 is a left elevation view thereof;

FIG. 17 is a rear elevation view thereof;

FIG. 18 is a front side elevation view thereof;

FIG. 19 is a top plan view thereof;

FIG. 20 is a bottom plan view thereof;

FIG. 21 is a top, front, left perspective view of the combined steering block C-hub;

FIG. 22 is a top, front, left, environmental perspective view of the combined steering block C-hub; and,

FIG. 23 is an enlarged detail view of the top, front, left, environmental perspective view of the combined steering block C-hub taken from a left section of FIG. 22.

Structural elements depicted by broken lines have been shown for the purpose of illustrating portions of the combined steering block and C-hub and its environment that form no part of the claimed design.
